CLAIM

The ornamental design for a label holder as shown and described.

DESCRIPTION

FIG. 1 is a bottom, front, left-hand side perspective view of a label holder showing our new design in an environment of use;

FIG. 2 is a top, front, left-hand side perspective view of a label holder shown in an alternate environment of use;

FIG. 3 is a bottom, front, right-hand side perspective view of a label holder;

FIG. 4 is a front elevational view thereof;

FIG. 5 is a back elevational view thereof;

FIG. 6 is a top plan view thereof;

FIG. 7 is a bottom plan view thereof;

FIG. 8 is a left-side elevational view thereof; and,

FIG. 9 is a right-side elevational view thereof.

The broken lines represent portions of the label holder that form no part of the claimed design, with the broken lines immediately adjacent the shaded areas represent the bounds of the claimed design. The other broken lines in FIGS. 1 and 2 represent the environment, which forms not part of the claimed design.
